UNITED STATES PATENT OFFICE.

CHARLES O. SHANNON, OF COLUMBUS, OHIO.

NECKTIE FASTENER.

Application filed January 16, 1922. Serial No. 529,769.

To all whom it may concern:

Be it known that I, CHARLES O. SHANNON, a citizen of the United States, residing at Columbus, in the county of Franklin and State of Ohio, have invented a certain new and useful Improvement in Necktie Fasteners, of which the following is a specification.

This invention relates more particularly to the type of necktie that is formed with a knot either imitation or real and when in place has two dangling ends in front of the shirt. Unless these dangling ends are somehow secured they occasion a great deal of annoyance to the wearer, especially in the summer when a vest is not worn. The object of the present invention is an improved means embodied in or made a part of the tie itself whereby said ends may be secured to the shirt and kept from flying about and annoying and inconveniencing the wearer.

The invention is embodied in the example shown and described, the feature of novelty being finally claimed.

In the accompanying drawing—

Figure 1 is a rear view of the necktie equipped with my invention.

Fig. 2 is a cross section on the line II—II Fig. 1.

In the views 5 is the knot which can be of the real or imitation or "made up" kind, and 6 and 7 the two ends before referred to. In made up ties the end 7 is usually somewhat narrower than the end 6 and includes a stiffening means so that it can be readily passed and drawn down through an opening provided for that purpose in the knot 5. In carrying out my invention the end 6 at its rear side has stitched to it at its vertical edges a piece of fabric 8 to form with the

end 6 an elongated loop or pocket open however at both the top and bottom so that the necktie end 7 can be passed down into or through it and the piece 8 manipulated with the fingers. The piece 8 is provided with one or more button holes as shown at 9 and 9^a whereby the piece 8 may be secured to a button on the shirt of the wearer of the necktie. Where a plurality of button holes is provided a nicer adjustment of the tie may be made for differences in the distances of the nearest appropriate button for fastening the tie.

With this invention it will be observed that both ends of the tie can be held neatly flat against the shirt and from any possibility of flying about to the annoyance of the wearer.

The invention can be used with equal advantage in both kinds of tie and the forms of the parts can be varied without departing from the gist of the invention as claimed.

What I claim is:

The combination with a necktie of the variety described, of a substantially rectangular piece of fabric secured by lines of stitches at its opposite vertical edges only to the rear side of one of the end portions of the necktie so as to form an opening for the insertion between it and said portion of the necktie of the other end portion of the necktie said rectangular piece formed with a button hole located between said vertical lines of stitches to engage a button on a shirt and thereby secure said necktie end portions close to the shirt front and prevent said portions from accidental movement with reference thereto.

CHARLES O. SHANNON.
